UNITED STATES PATENT OFFICE.

KARL SOHLER, OF BIEDERITZ, NEAR MAGDEBURG, GERMANY, ASSIGNOR TO FRIED.
KRUPP GRUSONWERK AKTIENGESELLSCHAFT, OF MAGDEBURG, GERMANY.

STRAINING PRESS.

Application filed April 29, 1926, Serial No. 105,537, and in Germany May 7, 1925.

My invention relates to improvements in straining presses for extracting liquids from moist substances of various kinds and more particularly to presses of the type having 5 a press chamber of annular cross section through which the material is passed, said chamber being mainly composed of two cylinders, one of the latter or preferably both being perforated and the moist substances being continuously fed and squeezed 10 through the space between said perforated cylinders.

The object of my invention is to provide a press of this character which is very 15 simple in its construction, containing no complicated parts as worms, safety couplings, gear wheels and the like, and which can be manufactured, sold and maintained at comparatively low cost.

Another object of my invention is to thus 20 design the feeding and discharging mechanism that the pressing action and the amount of material under treatment will be kept automatically practically constant 25 during the whole operation of the press.

With these and other objects in view I have invented a straining press for continuous operation the essential features of which are outlined in the appended claims.

The nature and scope of my invention will 30 be more fully understood from the following specification taken together with the accompanying drawings in which three preferred forms of my invention are illustrated by 35 way of examples.

Fig. 1 is a vertical sectional view of the press;

Figs. 2, 3, and 4 are similar sectional views 40 showing three modified forms of the feeding and actuating mechanism.

Like members of reference indicate similar parts in all the three modified embodiments of my invention.

Referring to Fig. 1 of the drawings the 45 annular press chamber 1 comprises two walls 2, 3 which are in their preferred form cylindrical, but which can be made conical or in part conical and in part cylindrical, without deviating from the essence of my invention.

Said members 2, 3 in their preferred cylindrical form are both provided with perforations 4, representing outlets for the discharged liquid.

The material to be treated is continuously

supplied through the hopper 5 and is fed and squeezed into the press through its intake 6 by means of a thumb 8 carried by a nave member 16 and mounted on the rotary spindle 7.

It will be noted that the pressure exerted by the thumb 8 upon the material is concentrated to a rather limited section of the whole annular intake area 6 of the press chamber, and thus the feeding and pressing 65 action is of a strictly one-sided or eccentric character.

In the modification of the press shown in Fig. 1 the inner straining cylinder 3 is rigidly mounted in the press and held in its 70 place by means of the hub 9 and the bottom plate 10.

The outer straining cylinder 2 is held in its place by means of a ring 11 surrounding its bottom edge and allowing of a rotary 75 tilting motion of the cylinder 2 as indicated in dot and dash lines.

The said tilting motion of the outer straining cylinder 2 is caused by the aforesaid one-sided squeezing action of the thumb 80 8 in such manner that the cylinder 2 will tilt towards the respective position of the thumb 8, i. e. the left when the thumb 8 passes along left side of the cylinder 2 as indicated in Fig. 1 in bold lines.

It will be noted that at the opposite (right) side the annular space 6 will be then contracted in turn accordingly, whereby the material under treatment is highly squeezed in radial direction and is compressed and 90 condensed in such manner that a substantially increased pressure occurs also in the axial direction through the whole press.

Owing to said combined radial and axial pressing effects the output of the liquid extracted from the material is considerably 95 higher when compared with the results obtainable heretofore.

The extracted liquid is discharged through the outlet ports 17^a, 18^a, while the material 100 after treatment is discharged at the discharge port 13 of the press chamber preferably by means of knives or scrapers 12, mounted on a rotary carrier 14.

I prefer to mount the scrapers 12 so as to 105 be capable of being lifted or lowered relatively to the press chamber and so as to project to a larger or smaller extent into the discharge port 13.

In the embodiment of my invention shown 110

in the drawings the controlling mechanism for the scrapers 12 consists of a lever 15, engaging the carrier 14, the latter being slidably mounted on the shaft 7.

5 Figs. 2 and 3 show straining presses according to this invention but of modified construction, in which the inner straining member 3 is tiltably mounted upon its carrier 10 and is positively actuated as to its 10 rotary tilting motion.

The means for imparting a positive tilting motion to the inner straining member 3 comprises a rotating eccentric 17 engaging the hub 9 of the straining member 3.

15 It will be noted in Fig. 2 that the eccentric 17 is mounted on the shaft 7 so as to have its eccentricity opposite to the thumb 8, while the reduced portion of the eccentric 17 registers with the position of the thumb 8.

20 In the modified construction shown in Fig. 3 the whole shaft 7 is given a rotary tilting motion by means of the eccentric 19, rotating within the rigidly mounted bearing 18. Said tilting motion of the shaft 7 is transmitted in turn to the inner straining cylinder 3. In all other respects the construction and the working conditions of this modified press are identical to that outlined in connection with Fig. 1.

30 Many structural changes and modifications will offer themselves to those skilled in the art in carrying my invention into practice. Thus e. g. the outer straining member 2 may be given a positive tilting motion e. g. through a rotary driving member engaging the head of said cylinder 2 at its inner periphery by means of a roller or a similar element. In this case the said roller should be arranged so as to be closely before or behind the feeding thumb 8 with regard to its respective position on the shaft 7 and the direction of rotation of the latter, the object being to provide an enlarged intake space in due register with the feeding action.

45 Fig. 4 shows a further modification in which both the inner and outer straining members 3 and 4 are tiltable, having spherical bearing surfaces 20 and 21 on their respective lower edges. Tilting motion is imparted to the inner straining member 3 by means of an eccentric 23 rigidly mounted on the shaft 7 under nave 22 of the pressing thumb 8, the nave 24 of the inner straining member loosely surrounding the eccentric. Tilting motion is imparted to the outer straining member 4 by the action of the pressing thumb 8 on the material in the annular pressing space. The discharging knives which operate in the outlet end of the annular pressing space and serve to scrape the material out of the same, are axially shiftable in the same manner as the pressing thumb 8, which makes it possible to regulate the pressure in the pressing space. In

the embodiment shown the pressing device 8 and discharging scrapers 12 are positively connected together by a system of levers in such a manner that with the automatic withdrawal of the pressing device the discharging scrapers are simultaneously moved in the same direction. The system of levers consists of the lever 26 which is pivoted to the frame of the press at 25 and whose free end is loaded by a weight 27, so that the 70 pressing thumb 8 always operates under a certain pressure, which may however be changed by shifting the position of the weight or by exchanging the same for a heavier or lighter one. The lever 26 is 80 linked to a ring 28 on nave 22. Lever 26 is connected to lever 15 by a rod 29. The lever 15 which is pivoted at 17 is pivotally connected to a ring 30 on the knife frame 14. The knife frame is shiftably but non-revolvably mounted upon the shaft 7. If the movement of the material in the pressing space is stopped by an increase in pressure, the pressing device rises which raises the lever 26 and causes the discharging scrapers 90 to penetrate deeper into the outlet end of the press, thereby increasing the discharge of material from the pressing space. When the pressure in the pressing space returns to normal the pressing thumb sinks again, 95 forcing the scrapers 12 back to their normal operating position.

The center of the tilting motion which is preferably in the longitudinal axis of the press and the plane respectively where the tilting of the straining member is zero may be located at any distance below the feeding member above or below the discharge port of the press conformably to special requirements.

100 Having thus described my invention, it shall be understood that I wish not to limit myself to any particular structural details described in the specification and shown in the drawings by way of examples, as various other changes than those indicated above may be made without deviating from the spirit and the leading ideas of my invention.

105 What I claim is:

1. A straining press comprising a pair of cages one inside the other and forming between them a space for the reception of material to be pressed, and means for relatively tilting said cages.

110 2. A straining press comprising a pair of cylindroidal cages of different diameter mounted one inside the other and forming between them an annular space for the reception of material to be pressed, and means for relatively tilting said cages.

115 3. A straining press comprising a pair of cylindroidal cages of different diameter mounted one inside the other and forming between them an annular space for the re-

ception of material to be pressed, and means for imparting a rotary relative tilting motion to said cages, whereby the material in said annular space is progressively squeezed and compressed in a transverse direction.

5. A straining press comprising a pair of cylindroidal cages of different diameter mounted one inside the other and forming between them an annular space for the 10 reception of material to be pressed, and means for imparting to one of said cages a rotary tilting motion such that it describes a cone whose apex lies on the longitudinal axis of the press

15. 5. A straining press comprising a pair of cylindroidal cages of different diameter mounted one inside the other and forming between them an annular space for the reception of material to be pressed, means 20 for tilting one of said cages, and a circular guide surrounding said tilting cage at the transverse plane where its tilting motion is zero.

6. A straining press comprising a pair 25 of cylindroidal cages of different diameter mounted one inside the other and forming between them an annular space for the reception of material to be pressed, a revolute shaft, an eccentric on said shaft, 30 and an eccentric ring rigid with one of said cages and cooperating with said eccentric, whereby a rotary tilting motion can be imparted to the cage to which said eccentric ring is secured.

35. 7. A straining press comprising a pair of cylindroidal cages of different diameter mounted one inside the other and forming between them an annular space for the reception of material to be pressed, one of 40 said cages being freely tiltable, means for feeding material to be pressed into one end of said annular space, and a pressing thumb working at the intake end of said annular space and adapted to be moved around the 45 same for pressing in new material to be pressed, whereby said tiltable cage is tilted so as to squeeze the material in the side of said annular space opposite to said thumb in a substantially transverse direction.

50. 8. A straining press comprising a pair of cylindroidal cages of different diameter mounted one inside the other and forming between them an annular space for the reception of material to be pressed, said cages 55 being tiltably mounted, means for feeding

material to be pressed into one end of said annular space, a revolute shaft within said cages, an eccentric on said shaft, an eccentric ring cooperating with said eccentric and rigid with one of said cages, a pressing 60 thumb secured on said shaft so as to rotate therewith and extending into the intake end of said annular space, the point of said eccentric furthest from the axis of said shaft being opposite to said pressing thumb. 65

9. A straining press comprising a pair of cylindroidal cages of different diameter mounted one inside the other and forming between them an annular space for the 70 reception of material to be pressed, means for feeding material to be pressed into one end of said annular space, an axially shiftable pressing thumb extending into the intake end of said annular space and adapted to be moved around the same for pressing in new 75 material to be pressed, and yieldable means for forcing said thumb against said material.

10. A straining press in accordance with claim 9 in combination with a discharging 80 scraper adapted to be rotated in the discharging end of said annular space, said scraper being shiftable longitudinally of said cages, and connections between said scraper and said pressing thumb such that the longitudinal position of said scraper 85 is dependent upon the longitudinal position of said pressing thumb.

11. A straining press in accordance with claim 9 in combination with a discharging 90 scraper adapted to be rotated in the discharging end of said annular space, said scraper being shiftable longitudinally of said cages, connections between said scraper and said pressing thumb such that the longitudinal position of said scraper is dependent upon the longitudinal position of said 95 pressing thumb, and means for varying the force of said yieldable means.

12. A straining press for the purpose set forth and having the features outlined in 100 claim 9 characterized therein, that the pressing thumb is axially slidably mounted with respect to said cages, and automatic means for controlling the working position of the pressing thumb, conformably to the 105 required working pressure of the press.

The foregoing specification signed at Berlin, Germany this 15th day of April, 1926.

KARL SOHLER.
